US0D1018048S

(12) **United States Design Patent** (10) **Patent No.:** **US D1,018,048 S**
(45) **Date of Patent:** **** Mar. 19, 2024**

(54) **DRAWER UNIT**

(71) Applicant: **ShenZhen YiHong Technology Co., LTD**, Guangdong (CN)

(72) Inventor: **Yi Dai**, ShenZhen (CN)

(73) Assignee: **ShenZhen YiHong Technology CO., LTD**, ShenZhen (CN)

(**) Term: **15 Years**

(21) Appl. No.: **29/918,158**

(22) Filed: **Nov. 26, 2023**

Related U.S. Application Data

(62) Division of application No. 29/899,799, filed on Aug. 13, 2023.

(51) **LOC (14) Cl.** **03-01**

(52) **U.S. Cl.**

(57) **CLAIM**

The ornamental design for a drawer unit, as shown and described.

DESCRIPTION

FIG. 1 is a perspective view from above of a first embodiment of a drawer unit showing my new design, wherein the drawer unit is shown with an inner container sliding out of a housing;

FIG. 2 is a perspective view of the housing;

FIG. 3 is a perspective view from below thereof;

FIG. 4 is a front view thereof;

FIG. 5 is a back view thereof;

FIG. 6 is a left side view thereof;

FIG. 7 is a right side view thereof;

FIG. 8 is a top view thereof;

FIG. 9 is a bottom view thereof;

FIG. 10 is a perspective view of the inner container;

FIG. 11 is a perspective view from below thereof;

FIG. 12 is a front view thereof;

FIG. 13 is a back view thereof;

FIG. 14 is a left side view thereof;

FIG. 15 is a right side view thereof;

FIG. 16 is a top view thereof;

FIG. 17 is a bottom view thereof;

FIG. 18 is a perspective view of the drawer unit with the inner container completely enclosed by the housing; and,

FIG. 19 is a perspective view of a second embodiment of the drawer unit with all views identical to that of the first embodiment, except for a perceivable degree of transparency.
